US0D1004759S

(12) **United States Design Patent** (10) **Patent No.:** **US D1,004,759 S**
(45) **Date of Patent:** **** Nov. 14, 2023**

(54) **JUICER FILTER**

(71) Applicant: **Ningbo Justice Engineering Plastic Mould Co., Ltd., Yuyao (CN)**

(72) Inventor: **Ruijiang Zhang, Yuyao (CN)**

(73) Assignee: **Ningbo Justice Engineering Plastic Mould Co., Ltd., Yuyao (CN)**

(**) Term: **15 Years**

(21) Appl. No.: **29/808,109**

(22) Filed: **Sep. 16, 2021**

(30) **Foreign Application Priority Data**

Mar. 16, 2021 (CN) 202130139958.X

(51) **LOC (14) Cl.** **07-04**

(52) **U.S. Cl.**

USPC **D7/667**

Assistant Examiner — David O'Brien

(74) *Attorney, Agent, or Firm* — Raymond Y. Chan; David and Raymond Patent Firm

(57) **CLAIM**

The ornamental design for a juicer filter, as shown and as described.

DESCRIPTION

FIG. 1 is a perspective view showing a first embodiment of my new design.

FIG. 2 is a front view of FIG. 1.

FIG. 3 is a rear view of FIG. 1.

FIG. 4 is a left end view of FIG. 1.

FIG. 5 is a right end view of FIG. 1.

FIG. 6 is a top view of FIG. 1.

FIG. 7 is a bottom view of FIG. 1.

FIG. 8 is another perspective view of the first embodiment of my new design.

FIG. 9 is a perspective view showing a second embodiment of my new design.

FIG. 10 is a front view of FIG. 9.

FIG. 11 is a rear view of FIG. 9.

FIG. 12 is a left end view of FIG. 9.

FIG. 13 is a right end view of FIG. 9.

FIG. 14 is a top view of FIG. 9.

FIG. 15 is a bottom view of FIG. 9; and,

FIG. 16 is another perspective view of the second embodiment of my new design.

1 Claim, 10 Drawing Sheets
